UNITED STATES PATENT OFFICE.

FRANK P. MACLENNAN, OF TOPEKA, KANSAS.

DESIGN FOR A NEWSPAPER-DISPENSING DEVICE.

46,405.

Specification for Design.

Patented Sept. 15, 19

Application filed July 25, 1914. Serial No. 853,172. Term of patent 7 years.

To all whom it may concern:

Be it known that I, FRANK P. MACLENNAN, a citizen of the United States, residing at Topeka, in the county of Shawnee and State of Kansas, have invented a new, original, and ornamental Design for Newspaper-Dispensing Devices, of which the following is a specification, reference being had to the accompanying drawing, forming part thereof.

The figure is a perspective view of a newspaper dispensing device, showing my design.

I claim:

The ornamental design for a newspaper dispensing device, as shown.

FRANK P. MACLENNAN.

Witnesses:

ALBERT A. MILLER,
C. C. BOOHER, Jr.
